UNITED STATES PATENT OFFICE.

HENRY BRAEN, OF PATERSON, NEW JERSEY.

BILL-FILE.

1,193,863.

Specification of Letters Patent.

Patented Aug. 8, 1916.

Application filed February 26, 1915. Serial No. 10,716.

To all whom it may concern:

Be it known that I, HENRY BRAEN, a citizen of the United States, residing at Paterson, in the county of Passaic and State of New Jersey, have invented certain new and useful Improvements in Bill-Files, of which the following is a specification.

This invention relates to apparatus for filing papers, and the like, such as bills, and it contemplates certain improvements in such apparatus designed to promote convenience and facility in filing and having access to the contents thereof for various purposes, especially in the use of the apparatus for the particular purpose for which it has been designed, *i. e.*, for the filing of accounts of customers of grocers and other tradesmen.

The invention consists, first, in a novel construction of a holder for bills or other papers; second, in a novel combination of a series of holders and a receptacle or case to contain them; third, in a novel means to releasably secure the holders in their case or equivalent; and, fourth, in a novel construction of a case or receptacle of a kind suitable to receive the holders or other articles.

In the accompanying drawings, in which the invention is fully illustrated, Figure 1 is a side elevation, partly in section, of one form of the apparatus; Fig. 2 is a front elevation, partly in section, of what is shown in Fig. 1; Fig. 3 is a sectional view on the line $x-x$ of Fig. 1; Fig. 4 is an enlarged sectional detail of the forward portion of the apparatus; Figs. 5, 6 and 7 show the several parts of one of the bill holders, and Figs. 7^a and 7^b are a fragmentary side elevation and a fragmentary sectional view of one of the holder members; Fig. 8 shows the parts of the holder in plan in assembled relation, the holder members being in the open position; Fig. 9 is a longitudinal sectional view of what appears in Fig. 8; Fig. 10 is a vertical sectional view through a stack of four of the holders, all but one of the holders appearing in diagrammatic outline for the sake of clearness; Figs. 11 and 12 are a side and rear elevation of another form of the apparatus, Fig. 11 being partly in section; Fig. 13 is a fragmentary top plan view of this modified form; and, Figs. 14 and 15 are enlarged fragmentary views illustrating the holder locking means shown in Figs. 11 and 12.

Referring to Figs. 6 to 10, each holder for

the bills and other papers comprises a sheath and two holder members which are pivoted together and are housed in said sheath, the construction being such that when the holder members are withdrawn from the sheath to an extent which is preferably limited one of them is capable of being, and in the preferred construction is actually by elastic means, swung apart from the other, so as to expose the papers held between the members. The said sheath *a* (Fig. 5) is formed of a rectangular blank of sheet metal or other stiff sheet material having opposite sides thereof rebent to form guideways *b* and having centrally thereof and parallel with the guideways a channel *c* and at one end of the channel a recess *d* and an upstanding stop *e* and at the rear end of the channel an aperture *f* formed with a restricted portion *g* extending to the adjacent or rear margin of the sheath, the aperture *f* and restricted portion *g* forming a key hole slot. The holder member *h* consists of a rectangular piece of stiff sheet material having opposite side portions thereof rebent to form grooves *i* and corresponding external reinforcing flanges (Fig. 10) and upstanding to form lateral walls *j*. Near the forward edge of the member *h* there is a finger hole *k*, and in the rearward edge are a recess *l* and a depending stop *m*, the hole, recess and stop being in the center line of the holder member. A loop-shaped spring clip *n* is suitably attached to the rear portion of the holder member *h* and upstands therefrom (Figs. 6, 8 and 9), having its free end bent forward slightly (Fig. 9). In the walls *j* of the holder member *h* near the back thereof are eyes *o*. An upstanding abutment *p* may be formed at the forward edge of the holder member *h*. The holder member *q* consists of a rectangular piece of stiff sheet material having a finger recess *r* formed at one end thereof and the edge thereof at the opposite end rebent or rolled, the portion of said piece which includes said edge being somewhat wider than the body of the member, in consequence of which the rolling of the material forms trunnions *s* (Figs. 7^a and 7^b). The edge of the piece in which the recess *r* is formed and the two side edges are bent upward to produce the walls *t t t* (Fig. 8).

The parts *a*, *h* and *q* are assembled as shown in Figs. 8 and 9. That is, the trunnions *e* of the member *q* are fitted into the eyes *o* of the member *h*. Upon member *q*

being then folded down upon member *h* against the tension of the spring clip *n* said members are introduced into the sheath at the rear end thereof. When properly housed 5 therein the forward edge of the member *h* is approximately coincident with the forward edge of the sheath. Upon grasping the member *h* at the abutment *p* and drawing forward thereon the stop *m* will abut 10 the stop *e* and limit such forward movement, and at or near the limit of the forward movement the member *q* will clear the sheath and the spring clip *n* will swing it to the open position (Figs. 8 and 9), the 15 member *h* being rigidly supported in the sheath because the part thereof beyond the pivot *s* with reference to the operator constitutes an extension, reinforced by the walls *j*, fitting the sheath. In this position, the 20 clip *n* holds the bills or other papers *u* secured in the member *q*, it being remarked that its free end is bent off slightly as aforesaid, to facilitate inserting and removing the bills. It will be understood that the 25 bills in this case are copies of those which the merchant has given to the customer to whom the particular holder appertains, and that the ledger account of this customer may be preserved on the sheet *v* which is kept 30 in the member *h*, its side edges fitting in the grooves *i* thereof. In the closed position of the holder members, the member *q* extends short of the forward edge of the member *h* and exposes the corresponding edge portion 35 of the sheet *v*, and on this edge portion may be inscribed the name of the customer to whom the holder appertains (Fig. 8). The opening *h* is designed to facilitate removal of the sheet *v* from the holder member *h*. 40 Referring, now, to Figs. 1 to 4, a case or cabinet is shown having a back wall *w*, a bottom wall *x*, two side walls *y* and a top wall *z*, the front edge of the side walls sloping forward; a partition 2 extends horizontally 45 across the cabinet and part way back, being spaced from the bottom wall *x* a distance sufficient to accommodate a drawer 3. The holders, one of which is above described, are arranged in the cabinet in as 50 many stacks (Fig. 2) as its width is designed to accommodate, the holders being arranged in stepped relation in each stack so that the customers' name inscribed on the sheet *v* will be exposed. A rod 4, slanting 55 at the same angle as the forward edges of the sides *y* of the cabinet, is journaled in the top wall *z* and in a bracket 5 on the partition 2, being received by the key hole slots in the sheaths of the holders and serving 60 to limit and thereby gage their backward movement so that when they all abut against the rod their stepped arrangement will be uniform. The thickness of the rod is less than the portions *g* of the key hole 65 slots, but its width is greater; when it

stands in the position shown in Fig. 5, therefore, each holder may be removed, but when it stands in the position shown in Fig. 8 the sheaths of the holders are held against removal, allowing the pair of holder members 70 to be drawn forward relatively to the limit afforded by engagement of the stop *m* with stop *e* and so as to cause the contents of the holder member to be exposed in the way explained. The several rods 4 have cranks 6 75 which are connected by the link 7 having a fork 8 in which engages a pin 9 on a lever 10 that is pivoted at 11 to the under side of the case and projects at the front (Figs. 1 and 3). Upon turning the lever it will be 80 observed that all the rods 4 are rotated to lock or unlock the holders in the various stacks.

It will be noted on reference to Fig. 10 that the bottom of each sheath *a* rests on 85 the rebent sides *b* of the sheath beneath, the channel forming portion thereof depending between said rebent sides and thus having the necessary clearance; to obtain the same result for the lowermost sheet in each stack 90 I provide on the partition 2 the spaced lining strips 12 (Figs. 2 and 4).

The cover for the open front side of the case or cabinet comprises two sections 13 and 14 hinged together at 15. The area of 95 the section 13 is about equal to that of the top wall *z*. It is connected to the side walls of the cabinet by two pairs of pivoted links 16 and 17. Said links are of approximately the same length—that is, one-half 100 the front to rear dimension of the top wall *z*. The links 16 are pivoted to the side walls near the top thereof and midway between their front and rear edges, and to the cover section 13 near its rear edge; the links 17 105 are connected to the front portions of the side walls about a link's length from the top to said side walls, and to the cover section 13 near its forward edge. The arrangement is such that the section 14 may be 110 folded back upon the section 13 from the position shown in Fig. 1 and then the two sections swung back on the links 16—17 so as to bring the section 13 resting flat against the top wall *z* of the case. The cover sections 115 are flanged at their edges, as shown, and when in the closed position the flange of the section 14 obstructs the removal of the drawer 3.

The apparatus shown in Figs. 11 to 15 is 120 substantially the same as that already described excepting as to the means for locking the holders in place. (These figures show that the apparatus may be set upon what is its back wall in Figs. 1 to 4, if desired, so that the entering and withdrawing movements of the holders are vertical instead of horizontal). The locking rod in this case is in the form of two leaves 18 pivoted together on a spindle 19 and foldable 125 130

against the tension of a spring 20 coiled about the spindle and having its ends bearing against the leaves, said spindle being mounted at its ends in the wall z' and a bracket x'' attached to the wall x' of the cabinet. Parallel bars 21 are pivotally connected to the ends of parallel links 22 pivoted to the wall x' , and these bars have co-acting lugs 23 between which the leaves of each locking rod are arranged. On moving the bars in the direction of the arrows, respectively, seen in Fig. 12, the locking bars, which are normally held by their springs expanded, will be collapsed. This may be accomplished by a lever 24 which is pivoted to the two bars 21 and projects upwardly out of the case or cabinet. The normal position of the parts is that shown in Fig. 12, where the collapsed locking rods are expanded. Therefore, since as shown the pivoted edges of the leaves are relatively upward, when a holder is inserted into the cabinet it will automatically become locked by the locking rod, which will be contracted first into more or less folded condition by the restricted portion f' of the key hole slot $f' g'$ of the sheath a' and then expand to the locking position shown in Fig. 14 as soon as the enlarged portion g' of the key hole slot is occupied by it. To remove a holder from the case of the cabinet, the lever 24 is swung to the left in Fig. 12, thereby collapsing the leaves of the locking rod.

Having thus fully described my invention, what I claim as new and desire to secure by Letters Patent is:—

1. In combination, folding members pivoted together, and a sheath in which said members have sliding movement, the free ends of said members being toward the mouth of the sheath and one member having a rigid extension portion at its other end formed with lateral upstanding walls and affording a support for said members in the sheath upon the other member clearing the sheath.

2. In combination, folding members pivoted together, and a sheath in which said members have sliding movement, the free ends of said members being toward the mouth of the sheath and one member having a rigid extension portion at its other end and formed with lateral upstanding walls extending into extension portion, the other member having pivotal support in said walls

and said extension portion affording a support for said members in the sheath upon said other member clearing the sheath.

3. In combination, a sheet metal sheath member and a sheet metal holder member 60 slidably arranged in the sheath member, one of said members having a longitudinal groove bent therein and a stop at one end of the groove and the other member having a bent-off projection reaching into said groove 65 and adapted to abut the stop.

4. In combination, a folding holder member having upstanding portions formed with opposite eyes and a complementary holder member of flat stiff sheet material having 70 lateral projections rebent into trunnion form and journaled in said eyes.

5. In combination, a folding holder member having upstanding portions formed with opposite eyes and a complementary holder 75 member of flat stiff sheet material having lateral projections at one end thereof and said end including the projections rebent, said rebent projections forming trunnions and being journaled in said eyes. 80

6. In combination, with a case and a stack of flat holders arranged therein with their forward portions in stepped relation to each other and provided with indices, a slanting bar forming an abutment means for 85 the backs of the holders and movable pivotally on a longitudinal axis into and out of locking engagement therewith.

7. In combination, a sheet-metal sheath member having opposite edges thereof rebent and forming guideways and having an elongated portion thereof between and parallel with said guideways bent downwardly in channel form and a stop at one end of the channel, and a holder member slidably 95 arranged in the sheath member and having a projection reaching down into said channel and adapted to abut the stop, the rebent edges of said sheath member being spaced from each other whereby to accommodate 100 between them the channel forming portion of another sheath member superimposed upon the first-named sheath member.

In testimony whereof I affix my signature in presence of two witnesses.

HENRY BRAEN.
